(57) **CLAIM**

The ornamental design for a pad for a firearm sling, as shown and described.

DESCRIPTION

FIG. 1 is a top, front, left perspective view of a pad for a firearm sling showing our new design, the bottom, rear, right perspective view being a mirror image thereof; and, FIG. 2 is a top plan view of the pad for a firearm sling of FIG. 1, the bottom plan view being a mirror image thereof. The broken lines showing portions of the design in all figures are included for the purpose of illustrating environment and unclaimed features and forms no part of the claimed design.

1 Claim, 2 Drawing Sheets
